CONCEALED HINGE

Otto C. Gessler, Detroit, Mich.

Application March 13, 1944, Serial No. 526,163

2 Claims. (Cl. 16—135)

1

The present invention relates to concealed hinge structures, and more particularly, to hinges for motor vehicle doors.

The primary object of the invention is to provide a concealed hinge structure of the above-mentioned type which may be securely and rigidly attached to one of the upright frame members of the vehicle body in such a manner as to prevent the inertia of the door when reaching its limiting point from bending or otherwise distorting the hinge structure and body structure of the vehicle.

Another object of the invention is to provide a hinge structure of the above-mentioned type comprising a comparatively small number of parts to become disorganized and to provide a hinge which may be quickly and easily constructed from blank stampings which likewise may be quickly and easily produced.

Another object of the invention is to provide a concealed hinge structure of the above-mentioned character in which the box portion of the concealed hinge may be quickly and readily attached to the frame structure of the vehicle so as to form an integral part of the frame structure and thereby prevent the weight of the door from causing the hinge to distort and sag the door and generally provide a concealed hinge structure which is rigid and stable.

Another object of the invention is to provide a concealed hinge structure of the above-mentioned character including a box-like hinge member formed from a blank stamping having tabs or projections formed integral therewith to facilitate the attaching and the fixing of the box-like hinge member to one of the vertical frame members or pillars of the vehicle body.

Another object of the invention is to provide a concealed hinge structure of the above-mentioned character in which the hinge strap is mounted to swing between a pair of parallel members which frictionally engage the hinge strap to retard the same and perform the function of a snubber and thereby prevent the door from being swung at a fast rate of speed during the opening movement thereof and causing damage to the frame of the vehicle and hinge structure.

Another object of the invention is to provide a concealed hinge structure for motor vehicle doors in which the parallel side members of the hinge box are connected at one end by a reenforcing strap so arranged with its ends overlapping the parallel wall members of the hinge box as to

2

provide additional support for the hinge pintle and to facilitate attachment of the box-like hinge member to the vertical frame member or pillar of a vehicle and by welding said strap or otherwise affixing the same to one of the flanges of said frame member or pillar.

Another object of the invention is to provide a concealed hinge structure of the above-mentioned type in which the base portion of the box-like hinge member is slotted adjacent one end to provide a tab projection adapted to be return bent over one of the edges of the vertical frame member or pillar and thereby additionally support the box-like hinge member and simultaneously space the base of the box or hinge member a slight distance from the wall of said vertical frame member or pillar for the major portion of its area.

Other objects and advantages of the invention 20 will become apparent during the course of the following description of the accompanying drawing, wherein:

Figure 1 is a horizontal cross sectional view 25 through a motor vehicle body structure illustrating an embodiment of the invention as applied thereto and showing the motor vehicle door swung to an open position in dotted lines;

Figure 2 is a vertical cross sectional view taken 30 on line 2—2 of Figure 1 and looking in the direction of the arrows to illustrate the manner in which anchoring tabs on the box-like hinge member are adapted for being fastened to the angular flanges of the vehicle frame member or pillar;

Figure 3 is a fragmentary side elevational view 35 of the frame member showing the manner in which the box-like hinge member is affixed thereto;

Figure 4 is a perspective view of a box-like hinge member showing the reenforcing strap at 40 one end thereof;

Figure 5 is a plan view of a blank stamping 45 from which the box-like hinge member is constructed;

Figure 6 is a perspective view of a modified form of the invention illustrating an anchoring tab punched out of the reenforcing strap to facilitate the attachment of the box-like hinge member to the vehicle pillar or frame member;

Figure 7 is a plan view of the form of the invention shown in Figure 6 illustrating the manner in which the blank is shaped and stamped to produce the hinge box as shown in Figure 6;

Figure 8 is a perspective view of a still further 50 modified form of the invention in which an an-

choring lug is struck out of the reenforcing strap for being received in an opening in the vehicle frame member or pillar post; and

Figure 9 is a perspective view of a form of the invention shown in Figure 8 showing the manner in which the reenforcing strap is applied to a hinge box.

In the drawing, wherein for the purpose of illustrating the invention like reference characters will be employed to designate like parts throughout, the attention is directed to the preferred embodiment of the invention shown in Figures 1 to 5 inclusive and as indicated in Figures 1 and 2 the invention is applied to a vehicle door construction in such a manner as to be concealed when the door is in its closed position. More specifically, the vehicle body and door structure comprises a vertical pillar post or channeled frame member 10 having flanges 11 and 12 arranged in parallel relation one to the other. Actually, the frame member or pillar post 10 has its lower end connected to the chassis frame as by means of welding or the like and said pillar post is slightly curved to conform to the body contour with the upper end connected to a frame structure of the top of the vehicle. The various body panels indicated as at 13 are connected to the pillar post 10 and as shown in Figure 1, the body panel 13 is provided with an offset portion 14 so that its flanged edge may be welded to the flange 12 of said pillar post. The door structure 15 is typical of a vehicle door and comprises an inner panel 16 stamped to provide side walls 17 having marginal flanges 18. An outer panel 19 is applied to the door panel 16 and has its edges return bent as at 20 over the marginal flanges 18 thereof as indicated in Figure 1.

The invention comprises a box-like hinge member generally designated by the reference character 21 and said box-like hinge member is formed from a stamping 22 as indicated in Figure 5, having a central portion providing a base 23 adapted to be folded along the transverse lines 24 so that the end members or portions of the blank 22 as at 25 may be bent in parallel relation to form side wall members 26. The blank 22 is stamped with tabs 27 and 28 and said tabs are adapted to extend through slots 29 and 30 formed in the flange 11 of the pillar post 10 whereby the free ends of said tabs may be bent over to interlockingly secure the hinge box 21 to the pillar post 10. In forming the blank 22, a pair of parallel slots 31 are stamped in the centralmost area 23 in opposed relation to the tab extension 27 and thereby form a tab 32 struck downwardly from the base 23 so as to space said base 23 from the flange 12 of the pillar post. The free end of the tab 32 is adapted to be return bent as at 33 over the vertical edge of the post 10 to further interlock the hinge box 21 in position.

The end portions 25 of the stamping 22 are punched as at 34 to provide a pair of opposed aligned openings for receiving a hinge pintle 35. Said hinge pintle extends through the eye 36 of a hinge strap 37 one end of which is arcuately curved as at 38 and extends between the side walls 26 so that the other end may be fastened to a bracket 39 carried by the door 15 by means of bolts or the like as at 40. Nuts 41 are threaded on each end of the hinge pintle 35 to securely hold the same in place. A reenforcing strap 42 has its ends angularly bent as at 43 to overlap the side wall portions 26 of the hinge box 21 and said overlapping end portions are provided with apertures or openings 44 adapted to align with the open-

ings 34 in said wall members 26 so that the hinge pintle 35 may extend therethrough and thereby provide a relatively large bearing surface for the ends of the hinge pintle and simultaneously strengthen and reenforce the box-like hinge member 21. The strap portion 42 may be welded to the flange 11 of the vertical frame or pillar post 10 so as to additionally strengthen the hinge structure and form a rigid connection between the hinge and said pillar post. The connecting strap 42 is adapted to hold the side walls 26 in frictional engagement with the hinge strap 37 so as to retard the swinging movement of the door 16 during opening and closing thereof, and if desired, the side walls 26 may be inclined slightly toward one another to increase the amount of friction on the arcuately curved portion 38 of the hinge strap 37 so that the required amount of retardation may be applied to the swinging movement of the door.

In the modified form of the invention, shown in Figures 6 and 7, the box-like hinge member is formed from a stamping 45 similar to the stamping shown in Figure 5 and said stamping is provided with a centralmost portion 46 forming the base of the box-like hinge structure as shown in Figure 6. The side walls 47 of the hinge structure are formed by bending the blank 45 upon the lines 48 similar to the form of the invention shown in Figures 1 to 5. As in the case of the form of the invention shown in Figures 1 to 5, the side walls 47 of the box-like hinge structure may be cut away as at 49 and the side walls are punched with openings 50 which are adapted to align as shown in Figure 6 and provide openings for a pintle pin similar to the pintle pin 35 in Figures 1 to 5 inclusive.

The opposite end of the centralmost portion 46 is slotted as at 51 to provide a central anchoring tab portion 52 which is adapted to be struck down so that the free end thereof may be bent over the edge of the pillar post 10 in identically the same fashion as shown in Figures 1 to 5. The opposite end of the centralmost portion 46 is connected to an extension 53 having wing-like tabs 54 on opposite sides thereof and said wing-like tabs are adapted to be folded on the lines 55 to form angular end pieces adapted to overlap the side walls 47 of the box-like hinge structure shown in Figure 6. The tab extension 53 is folded on the line 56 to provide a backing portion interconnecting the side walls 47 of the box-like hinge structure and said backing portion is slotted as at 57 to provide a punched out tab 58 adapted to be received in a slotted opening in the flange 11 of the pillar post 10. Openings 60 are formed in the wing-like tabs 54 so as to register with the openings 50 in the side walls 47 of the box-like hinge when said wing-like portions are arranged in overlapping relation therewith. It will thus be seen that the backing portion 53 strengthens and reenforces the box-like hinge structure by providing an increased bearing surface for the hinge pintle and simultaneously provides a struck-out tab 58 in the form of a lug adapted to be received and interlocked with the flange 11 of the pillar post 10 in a manner similar to the anchoring lugs 27 and 28 shown in Figures 1 to 5 inclusive.

In the still further modified form of the invention shown in Figures 8 and 9, the reference character 61 will generally be employed to represent the box-like hinge member having a base portion 62 and parallel spaced side walls 63 formed integral therewith. Adjacent one end

of the spaced walls 63 is formed a pair of aligned openings 64 for receiving a hinge pintle extending through the eye of a hinge strap.

Interconnecting the spaced parallel side walls 63 at one end thereof is a strap 65 which is formed of metal and is similar to the strap 42 and backing member 53 in the forms of the invention shown in Figures 1 to 7 inclusive. The strap is provided with angular end portions 66 which are adapted to overlie and overlap the spaced side walls 63 so that openings 67 in the ends thereof will register with the openings 64 and receive the ends of the hinge pintle, in substantially the same manner as the overlapping ends 43 and 54 of the strap 42 and backing member 53. The intermediate portion of the strap 65 is cut out as at 68 to provide an anchoring lug 69 adapted to enter the slot in the flange 11 of said pillar post 10 so as to securely anchor the box-like hinge member 61 in place. If desired, the remaining portion of the strap 65 may be welded in place to the inner surface of the flange 11 of said pillar post.

In each of the forms of the invention it may be desired to weld the strap 42, backing member 53 or strap 65 to the inner surface of the flange 11 in lieu of the anchoring lugs, or if desired, the anchoring lugs may have their free ends welded in place to integrate the structure and form a more rigid and solid construction.

It is to be understood that the forms of the invention herewith shown and described, are to be taken as preferred embodiments of the same and that various changes may be made in the shape, size and arrangement of parts without departing from the spirit of the invention or the scope of the subjoined claims.

What I claim is:

1. A hinge structure for supporting a vehicle door on a vertical channel frame member of said vehicle, comprising a box-like member adapted to be attached to the channel frame member, said box-like member having a base wall and

side walls connected thereto, a hinge strap secured to the vehicle door and projecting between said side walls, and a hinge pintle extending through an eye in said hinge strap and passing through aligned openings in said side walls, one end of said side walls and the opposite end of said base wall remote therefrom being provided with lugs for reception in apertures formed in the channel frame member whereby said channel member is gripped between the lugs of said base wall to secure said box-like member thereto.

2. A hinge structure for supporting a vehicle door on a vertical channel frame member of said vehicle, comprising a box-like member adapted to be attached to the channel frame member, said box-like member having a base wall and side walls connected thereto, a hinge strap secured to the vehicle door and projecting between said side walls, and a hinge pintle extending through an eye in said hinge strap and passing through aligned openings in said side walls, said side walls and the opposite ends of said base wall being provided with tab extensions forming anchoring lugs for reception and interlocking engagement in apertures located in said channel frame member whereby said channel member is gripped between the lugs of said base wall to secure said box-like member thereto.
